UNITED STATES PATENT OFFICE.

FREDERIC MARTIN, SR., OF COLUMBUS, OHIO.

WASHBOARD.

Application filed February 5, 1927. Serial No. 166,215.

This invention relates to improvements in wash boards, and has for an object the provision of a wash board involving substantial and durable features of construction and 5 wherein an improved arrangement of parts is provided for effecting the holding of bar soap used in connection with the board and to permit of the draining of soap solutions from said holding means onto the rubbing 10 surface or plate of the board so as to avoid waste of the soap and to assist in permitting the board to remain in a clean sanitary condition.

Another object of the invention resides 15 in constructing a wash board to include a cross bar or member, which constitutes an essential part of the frame of the board and which is utilized to serve as a ledge upon which the bar soap is retained when not in 20 active use, and also as a means for securing rigidly the upper edge of the rubbing plate to and within the frame.

The invention particularly consists in constructing and arranging the said cross member or bar so that the outer surface thereof lies substantially in the same vertical plane as the outer surface of the associated rubbing plate, so that when clothes or fabrics are being rubbed on the board, the said 25 cross member will offer no obstruction to the rubbing operation, will not interfere with the fingers or hands of the laundress and will occupy a position permitting the entire area of the rubbing plate to be utilized as a rubbing element, a feature which can not be accomplished when the soap supporting cross bar of the frame projects outwardly beyond the surface of the rubbing plate and offers an obstruction in the path 30 of free unrestricted rubbing strokes or movements.

A further object of the invention resides 40 in constructing the cross member to include a longitudinally extending groove in its front face which groove communicates with a slot arranged along the upper surface of the cross bar and by means of which soap drippings are permitted to pass through the slot and to travel longitudinally through 45 said groove flowing downwardly along the curved face thereof onto the rubbing plate, where such drippings may be utilized without waste.

Still, a further object of the invention 50 resides in providing the wash board with a metallic brand board, which constitutes a

part of the soap receptacle, and wherein this metallic brand plate is provided with offset flanges, receivable within grooves provided in the frame construction of the 60 board, the arrangement being such that the brand plate will occupy a position flush with the rear surfaces of the board frame and wherein a strong and substantial construction is provided at a comparatively 65 low manufacturing cost.

With these and other objects in view, as will appear as the description proceeds, the invention consists in the novel features of construction, combinations of elements and 70 arrangements of parts hereinafter to be fully described and pointed out in the appended claim.

In the accompanying drawing:

Figure 1 is a perspective view showing a 75 wash board comprising the present invention,

Figure 2 is a vertical transverse sectional view,

Figure 3 is a horizontal sectional view, 80

Figure 4 is a detail perspective of the brand board.

Referring more particularly to the drawings the numeral 1 designates my improved wash board in its entirety. This board 85 comprises a frame consisting of vertically extending transversely spaced side rails 2 having the inner surfaces thereof formed with sockets 3 for the reception of upper and lower cross members or bars 4 and 5 90 respectively and for the reception of the vertical edges of a metallic rubbing plate 6. The upper ends of the rails are suitably joined with a top bar 7 so that a rigid frame construction is produced.

The upper cross member 4 in this instance is formed to include a longitudinally extending recess 8 along the lower side thereof for the reception of the upper edge of the rubbing plate 6, while the upper portion of the bar 4 is formed with a second longitudinally extending recess 9 in which is positioned the lower edge of a metallic brand plate 10, which is also secured in connection with the side rails 2 and the top bar 7. 100 The ends of the cross member 4 are positioned within the upper ends of the sockets 3 and are suitably secured therein by means of fastening devices 11.

In this instance the cross member 4 is so 110 constructed that its outer surface 12 lies in a plane substantially flush with the rubbing

plate 6, so that the said upper cross member, and this is true also in respect to the lower cross member 5, will not offer an obstruction to the laundress when fabrics are being moved upwardly and downwardly over the surface of the rubbing plate. It is a common practice in wash board manufacture to form the cross members, particularly the upper cross member, which acts as a soap supporting ledge, so that the same will project outwardly some distance beyond the surface of the rubbing plate. When this is done the natural tendency on the part of a laundress is to diminish the length of the rubbing stroke, so that the hands will not contact with and be injured by the outwardly projecting portions of said cross members. As a result of this the effective length of the rubbing plate is appreciably diminished by the shortening of the stroke and naturally more manual effort enters into the operation. In the present construction a full stroke is permitted, enabling the laundress to utilize the full area of the rubbing plate and wherein injury to the hands is avoided.

The upper surface of the cross member 4 in connection with the adjacent portions of the rails 2, the back board 10 and the top bar 7, provides a pocket in which a bar of soap may be positioned when not in active use. Soap passed within this pocket is usually in a semi-soft condition and the present invention provides means whereby this soft dripping soap may be directed upon the rubbing surfaces of the plate 6. To this end the surface 12 is provided with a longitudinally extending groove 13, which includes a substantially horizontally extending upper wall and a convexed and curved lower wall. This groove is in communication with a forwardly and downwardly inclined slot 14 which opens at its lower end into the groove 13 and opens at its upper end into the soap pocket. By this construction it will be seen that the soap drippings are directed into the slot 14 and thence into the groove 13, and the curvature of the walls of

the slot and pocket is such that the drippings are permitted to spread over the surface of the bar 4 so as to be substantially uniformly distributed over the full width of the rubbing plate. It will be observed by this construction that provision is made for utilizing the soap to a maximum extent, preventing waste thereof and at the same time a structure is presented which will not interfere with the movements of the user of the board.

By reference to Figure 4 it will be observed that the brand plate 10, which is formed from a single integral stamping, is constructed to include marginal flanges 10^a which are receivable within correspondingly flat recesses provided in the bar 4, the side rails 2 and the top bar 7, the plate 10 being inserted in its operative position before the top bar 7 is finally fixed in place. The inclusion of the metallic plate 10 materially simplifies the process of manufacturing the board, produces a deeper soap receiving pocket and enables the plate to be positioned flush with the rear surfaces of the board as shown particularly in Figures 2 and 3.

What is claimed is:

In a wash board, a frame comprising a pair of transversely spaced parallel side rails having recesses in the inner opposite surfaces thereof, a transversely extending cross bar uniting said rails at a point intermediate their length, said cross bar being provided with a longitudinally extending recess, a top bar secured to the upper ends of said rails, and provided with a longitudinally extending recess, a rubbing plate mounted in said frame, and a metallic brand plate provided with angular marginal flanges offset therefrom, said flanges having outer portions fitting within the said recesses on said rails, top bar and cross bar, and said flanges having the inner portions thereof fitting against the inner faces of the side rails, the cross bar and top bar.

In testimony whereof I affix my signature.
FREDERIC MARTIN, Sr.
